UNITED STATES PATENT OFFICE.

ALEXANDER BOYNTON, OF SAN ANTONIO, TEXAS.

ROTARY REAMER.

Application filed October 23, 1924, Serial No. 745,456. Renewed May 5, 1926.

This invention relates to rotary reamers especially adapted for use in conjunction with oil, gas, or water wells.

The object of the invention is the provision of a rotary reamer of this character which may be advantageously used for the purpose of exposing a maximum amount of surface of the oil, gas, or water bearing formation whereby to increase greatly the production of oil, gas, or water wells.

Another object is the provision of a rotary reamer of this character which may be effectively utilized without wrenching, twisting or bending the drill stem and which may be easily withdrawn from the well even though the reamer blade be badly bent or twisted.

A further object resides in the provision of a rotary reamer having the advantages and capacities mentioned and which operates in such a novel manner as to keep the operator at the surface of the ground definitely advised of the progress of the reaming operation.

Other objects and advantages reside in certain novel features of the construction, arrangement and combination of parts which will be hereinafter more fully described and particularly pointed out in the appended claims, reference being had to the accompanying drawings, forming a part of this specification, and in which:

Figure 1 is a view in section showing the preferred embodiment of the invention and illustrating the same in inactive position as when the rotary reamer is being introduced into the well.

Figure 2 is a view similar to Fig. 1, but showing the rotary reamer as positioned at the completion of a reaming operation.

Figure 3 is a view in bottom plan of the apparatus as shown in Fig. 1, and

Figure 4 is a view in section on the line 4—4 of Figure 1.

Referring to the drawings the numeral 10 designates the lower end of a rotary drill stem. This rotary drill stem is hollow and is of conventional construction. It is to be understood that this invention is intended for use in conjunction with the usual equipment and machinery employed in the rotary drilling of oil, gas, or water wells, the usual rotary being employed for rotating the drill stem and the standard equipment ordinarily employed being utilized for lowering and raising the drill stem. The usual pumps

employed on rotary rigs are also utilized for the purpose of supplying water or fluid under pressure down through the hollow rotary drill stem to the reamer constituting the present invention. These instrumentalities are so widely employed and so well known in the art of drilling as to need no illustration here.

To the lower end of the hollow drill stem 10 a rotary reamer assembly constituting the present invention, and designated generally at 11, is connected, a sub 12 being employed for connecting the reamer assembly 11 to the drill stem 10.

The rotary reamer assembly comprises a cylindrical casing 12^a, the upper section of which is machined and formed to provide a cylinder 13. Below the cylinder 13 the walls of the casing are enlarged, as indicated at 14, in Fig. 4, and these enlarged portions of the casing wall define a transverse opening 15 at the lower end of the casing, the transverse opening 15 extending out through the periphery of the casing at one side and also extending down through the lower end of the casing. The upper ends of the enlarged portions 14 of the casing occur at the lower end of the cylinder and present shoulders 14^a. Preferably the side walls 15^a of the opening 15 are flat, plane and parallel. A reamer blade 16 is provided and has its upper end fitted in the opening 15, the flat faces 16^a on the reamer blade engaging the flat walls 15^a of the opening 15. The upper end portion of the reamer blade 16 is formed with a transverse opening 17 and through this opening a pivot pin 18 extends, the pivot pin having a free working fit in the opening 17. The ends of the pivot pin 18 are received in openings 19 in the enlarged portions 14 of the casing 12^a and both the extremities of the pivot pin 18 are swaged over, as at 20, to provide heads on the pins which are received in countersinks 19^a formed at the outer ends of the openings 19 whereby the pin 18 is effectively riveted to the casing which not only securely fastens the reamer blade 16 in position but at the same time prevents the supporting walls 14 from being bent or wrenching out of proper position. With this arrangement substantially the same portion of the reamer blade 16 is housed in the casing 12^a in all positions of the blade so that even though the free end portion of the reamer blade be twisted it

will not interfere with the return of the

blade to its vertical position and consequently will not interfere with the withdrawal of the reamer from the well. The blade 16 is provided with a cutting edge 21 which is presented outwardly and upwardly as the blade swings outwardly and upwardly from the vertical position shown in Fig. 1 to the horizontal position of Fig. 2.

Fluid pressure operated means is provided for swinging the reamer blade outwardly and upwardly as the reamer operation progresses and preferably this fluid pressure operated means includes a piston 22 having packing rings 23 and slidably fitted in the portion of the casing 12^a which constitutes the cylinder 13.

Motion transmission means is provided between the piston 22 and the reamer blade 16 and preferably comprises a rack 24 integrally formed with the piston and meshed with a gear segment or pinion segment 25 formed on the reamer plate 16.

The fluid pressure which is used to control the piston 22 in its downward movement is supplied from the pumps usually employed on rotary rigs, the pressure being carried from the pumps down through the hollow drill stem 10 and through a passage 26 in the sub 12 to the upper face of the piston.

Any fluid may be used as medium for transmitting the pressure from the pumps to the piston but usually a liquid, such as water, is employed and this same liquid is utilized at the proper time to wash the cut-

tings out of the well for the double purpose of cleaning out the well in the region of the reaming and for advising the operator that one stage of the underreaming action has been completed and that it is time to elevate

the drill stem, all as will more fully appear hereinafter. In order to carry out the two-fold purpose mentioned, the portion of the casing 12^a which constitutes the cylinder 13 is provided at one point with an inclined

port 27 which is controlled by the piston 22 in that the port is isolated from the fluid pressure at all times except when the reamer blade 16 approaches a horizontal position

when the piston 22 uncovers the port 27 and permits the port to communicate with the fluid pressure in the cylinder 13. The fluid pressure then forcibly discharges through the port 27 and washes the cuttings out of the well.

In operation, when the tool is being lowered into the well the reamer blade is held in the vertical position shown in Fig. 1 by virtue of the action of gravity. When the tool has been lowered to the bottom of the oil, gas or water bearing strata the pumps of the rotary rig are started and fluid under pressure is forced down through the hollow drill stem and through the passage 26 of the sub 12 to the upper end of the cylinder

13 wherein the fluid pressure is exerted on

the piston 22 that operates to force the piston 22 downwardly to swing the reamer blade 16 outwardly and upwardly. At the same time the drill stem 10 is rotated so that the reamer blade 16 is also bodily rotated as it swings. Centrifugal force aids in holding reamer blade 16 in the horizontal position as drill stem 10 is rotated for although when port 27 is opened the liquid pressure on piston 22 is somewhat relieved, the action of centrifugal force on the blade 16 at such time compensates for this loss of pressure. The pumps employed to supply the fluid pressure to the drill stem 10 and to the cylinder 13 will build up a high degree of pressure which is usually somewhere between three hundred and five hundred pounds per square inch. This supplies a tremendous power for the purpose of swinging the reamer blade outwardly and upwardly. Of course, when the pressure has been built up to maximum the pumps will become stalled and will so remain until the piston 22 has passed the port 27 to permit the liquid or fluid to forcibly discharge through the port and wash the cuttings out of the well. The appearance of the cuttings at the top of the well will advise the operator that the reamer blade 16 has reached a horizontal position and that one stage of the reaming operation has been completed. The action of the pump does this also. The drill stem 10 is then raised by the means ordinarily employed in conjunction with the rotary drilling of wells and the raising of the drilling stem returns the blade 16 to its vertical position, due to the engagement with the shoulder at the upper end of the reamed out section of the well. The operation above described is then repeated and may be carried out as often as desired. It is to be noted that by reaming upwardly the drill stem is prevented from swaying or flopping around in the hole and is thereby protected against wrenching or twisting and becoming corkscrewed or rainbowed.

It is to be noted that substantially the same portion of the blade 16 is housed in the opening in all positions, and this is believed to be an important and advantageous feature since the return of the reamer blade to the vertical which is necessary to permit it to be removed from the well is insured even though the outer end of the reamer blade is bent or twisted.

When the piston 22 has moved down in the cylinder 13 as far as it may, it engages the shoulders 14^a and it also engages a portion of the reamer blade. The reamer blade has a portion which engages the shoulder 11^a formed on the casing 11.

I claim:

1. In a rotary reamer for wells, a casing having a transverse opening extending out through its lower end and through one por-

- tion of its periphery adjacent its lower end, a single reamer blade having one end portion fitted in said transverse opening, means for pivotally connecting the reamer blade to the casing, said means including a horizontal pivot extending transversely of the casing to one side of its center, said casing having a cylinder formed therein, a piston operating in the cylinder and having a rack extending from its lower face at its periphery and engaging the periphery of the casing, said reamer blade having teeth meshed with said rack.
- 5 2. In a rotary reamer for wells, a casing, a reamer blade pivoted on the casing and swingable from a position in substantial alignment with the casing to a position substantially at right angles thereto, fluid pressure operated means for swinging the blade including a piston, said casing having a cylinder in which the piston is fitted, said casing having a port leading from the cylinder to the outside and located just above the lower limit of travel of the piston for permitting the fluid to escape when the blade is forced to a position at right angles to the casing, the action of centrifugal force tending to hold the blade in horizontal position.
- 10 3. In a rotary reamer for wells, a casing having a transverse opening extending out through the lower end and through one portion of its periphery adjacent its lower end, a single reamer blade having one end portion fitted in said transverse opening, means for pivotally connecting the reamer blade to the casing for swinging movement about a horizontal axis extending transversely of the reamer blade, said reamer blade being so swingable that substantially the same portion of the reamer blade is housed in the casing in all positions of the blade, the blade being swingable from a substantially vertical position in alignment with the casing to a substantially horizontal position at substantially right angles thereto, the casing having a shoulder engageable with the reamer blade when the reamer blade is in horizontal position, and fluid pressure operated means for controlling the reamer blade and comprising a piston, said casing having a cylinder in which the piston operates, a rack connected to the piston, gear teeth on the blade meshed with the rack, said piston having a portion engaging the reamer blade when the reamer blade is in a horizontal position, said piston also engaging the shoulder at the lower end of the cylinder and just above the transverse opening when the reamer blade is in horizontal position.
- 15 4. In a rotary reamer for wells, a casing, and a single reamer blade swingable from a vertical position in alignment with the casing to a horizontal position at right angles thereto, said reamer blade having a cutting edge presented outwardly and upwardly as the reamer blade swings from its vertical to its horizontal position, said cutting edge being presented along the upper horizontal edge of the blade when the blade is in a horizontal position so that the reamer is adapted to carry on an upwardly progressing reaming action.
- 20 5. In a rotary reamer for wells, a casing, a single reamer blade, means for pivotally connecting the reamer blade to the casing, said casing having a cylinder formed therein, a piston operating in the cylinder and having a rack extending from its lower face at its periphery and engaging the periphery of the casing, said reamer blade having teeth meshed with said rack.
- 25 6. In a rotary reamer for wells, a casing having a transverse opening extending out through the lower end and through one portion of its periphery adjacent its lower end, a single reamer blade having one end portion fitted in said transverse opening, means for pivotally connecting the reamer blade to the casing for swinging movement about a horizontal axis extending transversely of the reamer blade, said reamer blade being so swingable that substantially the same portion of the reamer blade is housed in the casing in all positions of the blade, the blade being swingable from a substantially vertical position in alignment with the casing to a substantially horizontal position at substantially right angles thereto, the casing having a shoulder engageable with the reamer blade when the reamer blade is in horizontal position, and fluid pressure operated means for controlling the reamer blade and comprising a piston, said casing having a cylinder in which the piston operates, said casing having a shoulder at the lower end of the cylinder, a rack connected to the piston, gear teeth on the blade meshed with the rack, said piston having a portion engaging the reamer blade when the reamer blade is in a horizontal position, said piston also engaging the shoulder at the lower end of the cylinder and just above the transverse opening when the reamer blade is in horizontal position.

ALEXANDER BOYNTON.
